UNITED STATES PATENT OFFICE.

NICHOLAS J. LE GRANDE, OF GOODWIN, ARKANSAS.

VALVE-GEAR FOR INTERNAL-COMBUSTION ENGINES.

1,345,094.

Specification of Letters Patent. Patented June 29, 1920.

Application filed February 14, 1919. Serial No. 276,939.

To all whom it may concern:

Be it known that I, NICHOLAS J. LE GRANDE, a citizen of the United States, residing at Goodwin, county of St. Francis, 5 and State of Arkansas, have invented certain new and useful Improvements in Valve-Gears for Internal-Combustion Engines, of which the following is a specification.

This invention relates to improvements in 10 valve gears for internal combustion engines, and has as its special object the provision of a novel and efficient type of valve operating means, the same being so arranged that the cylinder head can be removed in- 15 tact, together with the valve operating mechanism carried thereby, thereby allowing access to the cylinders in a ready manner.

A further object is to provide means 20 whereby, should wear occur to the valves or valve seats, that the same can be readily renewed and without a heavy expense.

These and other like objects, which will become more fully manifest as the description progresses, are attained by the novel construction and combination of parts hereinafter described and shown in the accompanying drawings, forming a material part of this disclosure, and in which:—

30 Figure 1 is a fragmentary vertical sectional view taken substantially through the center of a conventional type of explosion engine, and indicating the application of the invention;

35 Fig. 2 is an enlarged fragmentary sectional view, of the same, and

Fig. 3 is a transverse sectional view taken on line 3—3 of Fig. 2, drawn to a further enlarged scale.

40 In the drawings the numeral 10 indicates a hollow frame or casing, provided with enlarged bosses, 11, acting as bearings for the shaft 12, which is freely journaled therein, the ends of the shaft being rotatable in 45 outboard supports 14, adjacent to which is secured a drive wheel 15, from which power may be taken.

A central support 16, for the shaft is carried on a bar 17, which passes transversely 50 through the casing near its center.

A cover plate 20, is formed with downwardly extending flanged sides 21, the out-turned edges 22 of which are secured upon similarly outturned edges 23, formed with 55 casing.

Arranged internally of the casing 10, at

the upper end, and projecting into the cover 20, are pairs of cylinders 25 and 25', and 26 and 26' in which operate pistons 27 and 27' and 28 and 28', the same being connected 60 by piston rods 29 pivotally engaged within the pistons in the usual manner at one end, and connecting with the cranks 30 and 30' and 31 and 31' formed with the shaft 12.

Secured on top of the covered casing 20, 65 are hollow rectangular casings 35, having flanged bases 36, and formed with the casings are tubular sleeve guides 37, terminating in enlarged heads 38, from which project upward bracket elements 39, their front 70 horizontally extending portions constituting guides 40 being in register with the heads 38.

Valves 42, having stems 43, guided in the sleeves 37, enter the cylinders, the same seating against conical openings 44, formed in 75 the lower side of circular blocks 45, the blocks having extending flanges 46, suited to be received in counter-bore openings formed in the cover 20, which acts as the head of the cylinders.

These blocks are normally held in position by the flanges 36, of the casing 35, but obviously may be removed therefrom when wear occurs by releasing the casings 35, and new blocks substituted containing similar 85 valve seats. Collars 48 are fixed to the valve stems to prevent them dropping completely into the cylinders when the valve head is removed.

These valves are held normally against 90 their seats by means of coiled compression springs 49, surrounding the upper ends of the valve stems and bearing between the heads 38 and collars 52 secured by screws 51 on the projecting upper ends of the valve 95 stems. These collars are formed with convex upper surfaces 53, the same being pressed upward by the springs 49 so as to make contact with the lower curved surface 55, of forks 56, having between them spaces 100 57 through which extend the rods 50.

These forks are integrally formed with levers 60, extending diagonally downward, and pivoted on screws 61, set in the brackets 62, fixed securely upon the outer surface of 105 the cover plate 20. The oppositely extending downward ends of the levers 60, are also forked and carry pins 63, upon which are rotatably mounted rollers 64, impinging against the surface of cams 65, mounted at 110 suitable spaced intervals on a shaft 66, carried in bearings 67, extending outwardly

at the rear of the engine casing 10, said brackets are provided with removable caps 68, so that the shaft, together with the cams, may be readily removed when desired.

5   Rotary motion is communicated to the shaft 66, by reason of a bevel gear 70, fixed upon one of its extending ends, the gear meshing with a mating gear 71, fixed upon the upper end of a vertical shaft 72, guided 10 in a bracket 73, near its upper end, the same being attached to the end of the casing 10, while the lower end of the shaft passes through a similar bearing 74, extending from an arm 75 formed with the outboard 15 support 17.

Attached below the bearing 74, upon the vertical shaft 72, is another bevel gear 77, meshing with a mating gear 78, secured upon the shaft 12, exterior of the bearing 11. 20   Thus, when the engine is operated, rotary motion is conveyed to the shaft 66, causing the cams 65 to rotate and transmit reciprocating motion through the levers 60 to the rods 50, which, pressing upon the valve 25 stems 53, open the valves at proper intervals, their closing being effected by the springs 49.

In this type of engine it is customary to use separate inlet and exhaust valves for each of the several cylinders, all of which 30 are timed and operated in the usual manner. The intake and exhaust manifolds are indicated at 80 and 81 respectively in Fig. 2.

From the foregoing it will be obvious that 35 by disassociating the cover 20, the several valves and all of their attached parts, including the means by which they are operated, can be removed intact from the casing so that access may be had to the cylinder in an unusually easy and convenient manner.

40   Having thus described my invention, what I claim as new and desire to secure by Letters Patent is:—

1. In a valve gear for internal combustion engines, the combination with a casing, and 45 a cover secured thereto, of a plurality of cylinders formed with said casing extending to said cover, said cover forming the head of said cylinders, pairs of valves extending through said cover into each of said 50 cylinders in a direction parallel to the axes of the latter, said valves being all in alignment longitudinally of the engine, removable seats against which said valves make contact, means pressing said valves into engagement with said seats, levers pivotally 55

mounted on said cover and extending diagonally downward across said cover, said levers being adapted to operate said valves, a plurality of cams, one for each of said levers, a horizontal shaft mounted at the rear of 60 said cover, upon which said cams are secured, and means for rotating said shaft from the shaft of said engine.

2. In a valve gear for internal combustion engines, comprising a casing containing 65 cylinders, a cover common to all of said cylinders, a horizontal shaft, and means for driving said shaft from the shaft of said engine, of a pair of valves for each cylinder, a plurality of cams secured on said shaft, 70 levers mounted upon the cylinder cover, rollers in said levers contactable with said cams, interchangeable blocks having seats against which said valves contact, means for normally holding said valves against said 75 seats, sleeves rigid upon said cover adapted to guide the stems of said valve, rods slideable in said sleeves adapted to make contact with the ends of said valve stems, collars adjustably engaged with said rods, forks 80 formed in the upper ends of said levers adapted to make contact with said collars whereby said valves may be opened, and spring means in said sleeves adapted to maintain said valves in a normally closed 85 position.

3. In a valve gear for internal combustion engines, the combination with a casing, a plurality of cylinders therein, and a cover secured to said casing, said cover forming 90 the head of said cylinders, of a pair of valves extending through said cover for each of said cylinders, stems formed with said valves, rigid guides for said stems, means for holding said valves in a normally closed 95 position, rods slidably mounted in said guides, said rods being adapted to make contact with the upper ends of said valve stems, an adjustable collar secured to said 100 valve stems, forked levers engageable with said collars, said levers being fulcrumed on the upper part of said casing cover, a plurality of cams, one for each of said valves, said cams being operative with respect to 105 said levers, and means for communicating rotary motion to said shaft.

In testimony whereof I have affixed my signature.

NICHOLAS J. LE GRANDE.
